FLY SWATTER OR SIMILAR ARTICLE

Nathan W. Roop, Columbus, Ohio, assignor to
Columbus Plastic Products, Inc., Columbus,
Ohio, a corporation of Ohio

Application May 2, 1952, Serial No. 19,561

Term of patent 14 years

(Cl. D31—3)

To all whom it may concern:

Be it known that I, Nathan W. Roop, a citizen of the United States, residing at Columbus, in the county of Franklin and State of Ohio, have invented a new, original, and ornamental Design for a Fly Swatter or Similar Article, of which the following is a specification, reference being had to the accompanying drawing, forming a part thereof.

Fig. 1 is a perspective view of a fly swatter or similar article, showing my new design;

Fig. 2 is a top plan view thereof;

Fig. 3 is an edge elevational view;

Fig. 4 is a transverse sectional view taken on the line 4—4 of Fig. 2; and

Fig. 5 is a similar view on the line 5—5 of Fig. 2.
I claim:

The ornamental design for a fly swatter or similar article, substantially as shown.

NATHAN W. ROOP.
